(57) **CLAIM**

The ornamental design for a low voltage connector barrel for lithium ion battery module, as shown and described.

DESCRIPTION

FIG. 1 is a top perspective view of a low voltage connector barrel for lithium ion battery module showing our new design;

FIG. 2 is a front elevational view thereof;

FIG. 3 is a front bottom perspective view thereof;

FIG. 4 is a front and top perspective view thereof;

FIG. 5 is a front right side perspective view thereof;

FIG. 6 is a front left side perspective view thereof;

FIG. 7 is a rear elevational view thereof;

FIG. 8 is a bottom perspective view thereof;

FIG. 9 is a rear and top perspective view thereof;

FIG. 10 is a rear bottom perspective view thereof;

FIG. 11 is a rear left side perspective view thereof;

FIG. 12 is a rear right side perspective view thereof;

FIG. 13 is a top plan view thereof;

FIG. 14 is a bottom plan view thereof;

FIG. 15 is a right side elevational view thereof; and,

FIG. 16 is a left side elevational view thereof.
